UNITED STATES PATENT OFFICE.

HOWARD S. FOLKER, OF MILL VALLEY, CALIFORNIA, ASSIGNEE TO THE NATIONAL SAFETY APPLIANCE COMPANY, OF SAN FRANCISCO, CALIFORNIA, A COMPANY OF CALIFORNIA.

RAILWAY TRAIN CONTROL.

Application filed January 22, 1921. Serial No. 439,060.

To all whom it may concern:

Be it known that I, HOWARD S. FOLKER, a citizen of the United States, and a resident of Mill Valley, county of Marin, State of California, have invented certain new and useful Improvements in Railway Train Controls, of which the following is a specification.

This invention relates generally to improvements in train control mechanism for use on railways, in which there is provided magnetic means fixed on the roadbed co-operating with magnetic means carried by the railway locomotive or other railway vehicle by means of which when one magnet is in the field of the other the pneumatic train stop is operated to cause the application of the brakes.

The above statement describes generally 20 that which is common between the present invention and the invention disclosed in my pending application for patent, Serial No. 419,907 filed October 27, 1920.

The invention when specifically considered is applicable to railway control systems known as "vacuum" systems (used largely in European countries) as distinguished from the pressure and exhaust systems used largely in the United States, 30 which latter system is the particular subject matter of my previous application Serial No. 419,907, filed October 27, 1920.

One of the objects of the present invention is to provide a structure and installation which is simple, compact, easily constructed and maintained, positive and reliable in operation and low in construction, installation and maintenance cost.

Another object of the invention is to provide a structure in which light moving parts may be utilized, giving higher speed of operation; also to provide a mechanism which is devoid of springs the presence of which are well known causes of weakness and un- 45 certain or faulty operation.

Another object of the invention is to provide improved means for effecting the application of the brakes in the event that the inductor planes of the duplex control valves carried by the locomotive or tender should become broken.

Another object of the invention is to provide means for protection against over strong magnets in the duplex control valve structure and provide a structure which 55 will operate effectively when the train is going in either direction, or in the event that the track magnet be placed to lie in either direction.

Another object of the invention is to provide a train stop having the required mechanical structure in order to operate in a "vacuum" brake system.

Another object of the invention is to provide a device which is capable of operation 65 on a "vacuum" system even when the vehicle is moving at an extremely high speed and is in but momentary co-operation with the control magnet or other operating means.

Another object is to provide a release cock of improved construction by means of which it is applicable for installation in a "vacuum" brake system.

Other objects will appear from the subjoined specification and claims when read in connection with the accompanying drawings, in which:

Fig. 1 is a diagrammatic plan of a section of a railway track showing adjoining blocks 80 and disclosing a track magnet and its controlling means and also the duplex controlling valve unit which is carried by the vehicle and which co-operates with the track magnet.

Fig. 2 is a side elevation of the same.

Figs. 3, 4 and 5 are details in plan and elevation of the permanent track magnet and the electro-control magnet mounted adjacent thereto.

Fig. 6 is a diagrammatic view with parts in section and other parts broken away illustrating a complete control unit carried by the train and connected to the train vacuum pipe.

Fig. 7 is a top plan view of the improved duplex control valve structure with inductor planes.

Fig. 8 is a sectional view taken on line 8-8 of Fig. 7.

Fig. 9 is a section at right angles thereto on line 9-9 of Fig. 7.

Fig. 10 is an enlarged detail in section of a portion of one of the magnetically operated valves of the duplex control valve.

Fig. 11 is an elevation of the same with a portion broken away.

Fig. 12 is a plan of the armature for moving the said valve.

Fig. 13 is a horizontal section through line 13-13 of Fig. 10.

Fig. 14 is a section of the improved train stop showing the same in connection with the train vacuum pipe, the main valve being shown in closed position.

Fig. 15 is a fragmentary section of the structure shown in Fig. 14, the valve being shown in open position.

Fig. 16 is a vertical section of the release cock.

Fig. 17 is a side elevation of the same.

Fig. 18 is a view, partly broken away, in side elevation of part of a locomotive and also of a portion of the track and the control apparatus, showing the relative positions of the apparatus carried by the locomotive and supported by the track.

Fig. 19 is a diagrammatic view representing the local circuits at each track magnet location.

In the interest of clearness the specification will be divided into three parts. In the first part there will be described the general assemblage of the various elements of the installation, their relative positions and the effect of one upon the other. In the second part, each mechanism will be treated serially and its operation described, and in the third part, the operation of the system as a whole will be clearly set forth.

This invention is designed as an adjunct to fixed block or interlocking signal systems; it is constructed for interconnection with the same, and its operation is controlled as in such visible signal systems. Automatic stop operation is caused whenever a condition is produced which would cause a standard automatic semaphore signal to assume the stop position and should the engineer fail to obey the fixed signal indication.

The invention is also operable when the signals are actuated manually, in this instance suitable circuits along the track being provided to control the operation of the electro control magnet.

The track apparatus consists of a permanent magnet mounted on the ties in the center of the track, its length paralleling the rails, and its upper surface being preferably about one inch below the upper surface thereof. An electromagnet control unit is positioned below and across the poles of the permanent magnet and is of superior power when energized. Its control is through the standard track and line circuits of any standard automatic signal system, current from standard signal battery being supplied

to the electromagnet control unit through a local control circuit for clear movements only, and only while the train is passing through a short local track section. The control is provided as desired, for either or both directions of traffic. Normally the magnetic field of the permanent magnet is in place for automatic stop operation, and it is diverted only for clear movements by energizing the electromagnet control unit.

Referring first to the track installation shown in Figs. 1 to 5 and 18 and 19 inclusive, 10 represents the supporting rails of a suitable railroad mounted on ties 11, the same being divided into blocks x' , y' , and z' , &c., by the insulations 12. In each block, as illustrated, there is positioned a short distance below the rails, a polarized permanent track magnet 13 preferably of the horseshoe type and also an electrocontrol magnet 14 in which there is a core 15 and a coil 16, and extended pole pieces 17 and 18 which preferably because of the naturally cramped position of the mechanism, flare outwardly and upwardly in order to be operatively associated with the opposite poles of the track magnet 13. The respective pole pieces of the track magnet and of the electrocontrol magnet are marked N and S to distinguish their polarities, as shown. The polarized permanent track magnet is secured to the ties in any suitable way and the electrocontrol magnet is secured to the track magnet in order to hold the two in operative position, one with respect to the other, and this structure is normally covered in any suitable way.

The general structure and operation of the polarized permanent track magnet and the electrocontrol magnet is disclosed in my prior application Serial No. 419,907, filed October 27, 1920, in which the electrocontrol magnet is positioned adjacent the poles of the permanent track magnet with the poles reversed with respect to the poles of the permanent magnet to provide a means for deflecting the field of the permanent magnet and during such deflection, distorting the magnetism of said permanent magnet, thus permitting free passage thereover of the locomotive and train.

The locomotive apparatus consists of a magnetopneumatic control valve unit (for receiving stop actuation from the permanent magnet on track); a pneumatic stop valve (for causing an automatic brake application) and a release cock or valve. The magnetopneumatic control valves are hung in tandem below the locomotive or tender and said valves are provided with extended inductor planes in parallel, said planes having flat pole pieces adjusted to ride over poles of the permanent track magnet at a clearance of five to six inches, more or less. The polarity of one magnetocontrol valve is posi-

tioned opposite to that of the other, ensuring stop actuation regardless of locomotive heading. Each valve is normally held closed by its permanent duplex magnet, to the armature of which is fastened the valve stem. The valve is open when the armature is away from its magnet poles.

The pneumatic train stop is situated at a convenient location in the cab and is inserted 10 in the train vacuum pipe. The operation of this stop valve is controlled by the magneto-control valves and when operated, brake application is made either service or emergency, as provided for needs of train service.

15 The release cock or valve provides for a release of the brakes after automatic stop application has been made and may be so situated outside of the engine cab that the engine man must dismount from the cab 20 before he can operate said valve to release the brakes. These pieces of apparatus constitute what is known as the engine equipment and are connected by suitable pipes or air conduits leading to the brake pipe and 25 in the operation of which the "vacuum" is either made or destroyed.

Duplex control valve.

The duplex control valve unit F is 30 cased preferably in a cast brass housing and it is suspended from a connection flange 20 to which it is bolted by suitable screw-threaded bolts b. The flange 20 is suspended by rigid hangers 21 from the center sills S of the locomotive tender, or in 35 any other suitable place that conditions may make desirable. The duplex control valve is carried in spaced relation above the tracks or running rails of the railway and extends 40 in a line parallel to the rails. The cast brass housing 22 is provided with four lugs 23 situated respectively at the four corners of the plate through which pass the screw-threaded bolts b which secure the valve 45 housing to the connection flange 20 from which it is suspended. On either side of the valve housing and integral with it are four extending hubs or lugs 24 each of which is of the same construction and for- 50 mation and only one need therefore be described. Each of these lugs is provided with axial bores and in each of which is mounted a core or pole piece 25, made of a material of high permeability such as Norway iron. 55 These cores or pole pieces are screwthreaded at each end as at 26 and 27, the inner ends 26 engaging the screwthreads in the magnet pole pieces 28, and the external ends or pole pieces are fastened by suitable screw- 60 threaded nuts 29 to the cast iron inductor planes P which are also secured to the lugs of the housing by four cap screws 30 and lock washers 31.

On the ends of the extension hubs or lugs 65 24 of the duplex magnet casing are fitted

non-magnetic bushings 34' to sufficiently reduce the magnetic force flowing from one pair of duplex magnets to the other so that the holding force on the armature will not be reduced too much.

70 Mounted inside the valve housing are two magnetopneumatic valves V, one situated at each end thereof. The structure of each of these valves is the same, but the duplex magnets M and M' are arranged in pairs, 75 one pair having a polarity opposite to that of the other pair. The duplex magnets M and M' are securely clamped to the pole pieces 28 by magnet binders 32 and cap screws 33, as clearly shown in the drawing. 80 The cap screws 33 pass through the magnet binder 32 which is recessed to fit the ends of the magnets and hold them in spaced relation to each other, as clearly shown in 85 Figs. 8 and 9.

The pole pieces 28 are screwthreaded at two points to secure respectively the cap screws 33 for the pole piece binder 32 and the screwthreaded end 26 of the core 25 thereto. The pole piece extensions 25 are 90 secured in fixed relation to the lugs 24 by means of set screws 34 and lock nuts 35.

95 It is preferable to construct the valve parts of bronze and all chambers and recesses thereof are concentric with the external surfaces of the valve stems.

A disc 41 (Figs. 10 and 11) which, for clearness will be termed a pole piece disc, is provided in its periphery with four 100 equally spaced round holes. Into two of these holes which are diametrically opposite each other, are fitted a pair of pole piece dowels 42, and through the other two holes pass the valve body screws 40. The pole piece dowels 42 pass down through and 105 snugly fit the holes 42' in the under side of the magnet pole piece 28, the pole piece disc 41 resting on the top inside part of the pole pieces 28, as shown in Figs. 8, 10 and 11. The dowels 42 project a little below 110 the pole pieces 28 to ensure a good contacting surface with the armature 45.

The valve element 44 is constructed with a rectangular slot 46 in the top thereof, the slot extending diametrically across and being wide and deep enough to allow the armature 45 to operate freely. Armature guide pins 47 are secured to the valve body and project perpendicularly therefrom and are situated in the center of the slot, one near 115 each end or near the periphery of the valve body. These guide pins serve as guides for the armature 45. Screwthreaded holes 49 are situated at right angles to the slot, one in each side of the valve body to receive 120 the valve body screws 40 which pass down through the pole piece disc.

125 The armature 45 is provided with three equally spaced holes which extend therethrough, the center hole fitting the valve 130

stem 50 and the two holes near the end fitting the brass guide pins 47. As described above, these guide pins extend up through the holes in the armature and prevent it 5 turning on the valve stem and keep it in alignment with the pole piece dowels 42. The valve stem 50 is constructed of bronze; it is cylindrical in form and is provided with different diameters, the circumferences 10 being concentric to one another. The top end is smaller in diameter and is screw-threaded as at 51 to receive the screw-threaded acorn nut 52.

The valve proper is doubly seated, the top 15 seat V being disc shaped and seating against the valve seat rubber 53. On the under side of the disc shaped portion V is an annular shaped valve seat 54 which seats against the gasket 55 which is clamped between the 20 housing 22 and the bottom cap 70.

In order to mount the valve and armature, a washer 56 is first placed on the small end of the valve stem 50. The valve seat rubber 53 is placed in the valve body 44 and the 25 valve seat bushing 57 is next placed against the valve seat rubber 53. The armature 45 is fitted over the armature guide pins 47, and the stem 50 with the valve *v* to which it is attached entered into the bushing 57, the 30 screwthreaded end 51 passing up through the hole in the center of the armature 45. The acorn nut 52 is then screwed on tight against the end of the valve stem, thus forming a jam and allowing the valve stem 50 to 35 turn freely without turning the armature. The valve bushings 44 are fitted through the holes in the bottom of the housing 22, and the rectangular slot 46, as above described, straddles the pole piece dowels 42, as shown 40 in Fig. 11. These valve bushings are securely clamped against the under side of the pole pieces 28 by the valve body screws 40 which pass down through the disc 41 and screw into the valve bushings 44 as described.

The armature 45 is attracted and held 45 against the bottom faces of the pole piece dowels 42 by the magnetic force of the magnets M and M', thus holding the valve *v* seated against the flexible valve seat 53, as shown in Fig. 10. The atmospheric pressure on the top side of the flexible seat 53 forces it down against the valve *v*, thus sealing the joint between the valve *v* and the inside wall 55 of the bushing 57. When the armature 45 is away from the pole piece dowels 42 the bottom part 54 of the valve *v* seats against the gasket 55, thus closing the opening into the passage 132 (Fig. 9). 60 In the inner wall of the bushing 57 there is provided a port 134 so positioned that when the armature 45 is released and consequently is away from the pole piece dowels 42, and the valve *v* is in its lowermost position, atmospheric communication will be permitted

to take place between the chamber 133 past the disc of the valve *v* into the passage 131. The bushing 57 is held in fixed operative position with the port 134 and in registry with the passage 131 by means of a small dowel 70 57' in the bottom of the cap 70 which cap is preferably constructed of cast brass.

Extending up from the top face or flange of the cap 70 and securely fastened therein are two connecting tubes 131' and 132' the 75 upper ends of which are securely fastened to suitable fittings so that the tube 132' connects the horizontal passage 132 to the pipe 128, and the tube 131' connects the horizontal passage 131 to the pipe 130. In the pipe 80 128 (Fig. 6) adjoining its point of connection with the upper end of the tube 132' is a restricted passageway 128' for a purpose to be hereinafter described. The cap 70 is secured to the bottom of the housing by suitable cap screws 70'.

In the passage 131 at the point where the passage 137 (Fig. 7) crosses, is seated a ball 90 check valve 150 of the double action type. Two valve seats 145 are pressed into the passage 131, one on each side of the point where the passage 137 enters therein. In the entrances to the passages 137 are placed stop pins 147 to prevent the ball 150 from covering the same.

In order to conveniently assemble this valve structure, I have provided a hole into which a plug 144 is secured after the ball valve 150 is inserted therethrough and placed into the passage 131.

In the frame work of the inductor planes there are provided air passages 136 which pass through safety fittings 124 and safety nipples 125, Fig. 7, connecting with the passages 137. Protection to the system is provided against broken inductor planes by constructing the same of cast iron with these hollow passages 136 running therethrough. In the event that these planes become broken, the vacuum will be destroyed and the application of the brakes brought about in the same manner as though the valve V were opened in the regular way.

Each pair of duplex magnets being of opposite polarity, if one pair should become 115 stronger or one weaker than the other, the stronger acts on the weaker in the same manner as the track permanent magnet acts upon the duplex magnet.

Train stop.

120

The train stop of this system comprises a valve structure which is automatically operated by differences of fluid pressure controlled by suitable means which in this particular instance is a magneto pneumatic valve which has been described above. The train stop valve is designed particularly to be used for automatically applying the "vacuum" operated brakes of the railway 125 130

train. The admission of atmospheric pressure into a certain chamber of the valve mechanism will cause the train stop to operate, giving application to the brakes.

5 The structure of the train stop valve will now be described and its operation will be clearly understood therefrom.

10 The part 212 represents the connection flange into which all the pipe connections lead and it is provided with a flat surface on one side to which the valve body D is bolted with suitable cap screws 211 as will be well understood. In mounting the structure a gasket 214 is inserted between the connection flange 212 and the valve body D ensuring 15 against leakage between the several air passages. The valve body is cylindrical in form, the outer and inner surfaces being concentrically arranged.

20 Extending lengthwise or perpendicularly through the wall of the valve body are bolt holes for the entrance of the cap screws 211 which hold the several members together. In placing the parts together, dowel pins 213 are utilized to ensure against incorrect assembly of the several members. Into 25 the body of the valve D there is pressed a valve seat 202 which is annular in shape. Just below this valve seat are arranged a plurality of radial ports e, the function and operation of which will be described later.

30 The valve 203 is of the flat disc type and is provided with a rubber washer 204 as is shown. Equally spaced around the outer edge of the valve 203 are a plurality 35 of guide pins f which guide the valve and hold it in alignment in the chamber A, and which also act as stops to arrest the upward travel of the valve 203 by impinging 40 against the face of the flange 212.

45 The chamber A is isolated from the chamber B when the valve 203 is upon its seat 202. The bottom wall of the chamber B is formed by means of a flexible diaphragm 209 which is held in spaced relation with the valve 203 by the spacer 205 which is 50 spool shaped and which is mounted upon the shank of the bolt 206. On the lower side of the diaphragm 209 is a disc 210 which supports the diaphragm 209 against atmospheric pressure from the chamber B and ensures a greater effective pressure on 55 the diaphragm to hold the valve 203 on its seat, as will be fully hereinafter explained.

60 The screwthreaded bolt 206 with the attached guide stem 206' passes up through the center of the disc 210 and the diaphragm 209 and screws into the hub of the valve 203. On the end which protrudes through the valve is secured a nut 207 which forms a jam against the hub of the valve 203, thus preventing the several parts from becoming loose.

65 The diaphragm 209 is securely clamped

between the valve body D and the vacuum chamber head 208, which head is secured to the other members by cap screws 211, as above described.

A passage 250 is provided in the head 208 to connect the chamber C with the passage d, which latter connects to the pipe 130. In the center of the head 208 is a hub provided with an axially situated rounded hole serving as a guide for the stem 206' of the bolt 206 in which it freely fits and reciprocates.

Release cock.

The body of the release cock 368 (Figs. 80 16 and 17) consists of a semi-rectangular bronze casting with a cylindrically shaped boss 369 at the bottom thereof. A tapered key 304 is entered through the boss 369 into the chamber 375, the small end being 85 flattened and fitted into a lever handle 302 which operates in a rectangular slot above the chamber 375. The flattened end of the key 304 is so fitted that when the handle 302 is moved from one side to the other, 90 the key is rotated. Pressing against the larger end of the key 304 and encased in the boss 369 is a spring 303 for the purpose of holding the key 304 firmly in its seat. The boss 369 is provided with a 95 screwthreaded opening into which the screwthreaded plug 305 enters and engages against the spring 303.

The openings or entrances to the chamber 375 are screwthreaded to provide connecting means for suitable pipes and fittings. The chamber 375 is constructed with the ports so arranged that when the handle 302 is in "running position" the passage 100 from the pipe 118 to the pipe 128 is open 105 and the port 376 is closed. When the handle is in "released position" the passage from the pipe 118 is closed and the passage connected to the pipe 128 is open to the atmosphere through the port 376.

110 The release cock 368 may be so located on the locomotive that in order to gain access thereto the engineer or engine man must dismount from the cab.

115 The release cock is interposed between the pipe 118 which leads from the vacuum chamber of the brake equipment and the pipe 128 which is connected to the duplex control valve F so that when the handle 302 is in "running position" there is a direct 120 passage from the brake vacuum chamber to the magnetopneumatic duplex control valve and the port 376 is closed. In order to restore the valve of the duplex control valve to normal position after an operation, the 125 handle 302 is placed in "released position". Communication from the brake vacuum chamber through the pipe 118 to the duplex control valve through the pipe 128 is cut off by the key 304 and any vacuum in 130

the passages 132 and pipe 128 will be destroyed, through leakage or otherwise, by the diminution of atmospheric pressure through the port 376 into the pipe 128.

- 5 When the valve of the duplex control valve F has returned to normal position, the vacuum must again be produced in the pipe 128 and passages 132. This is done by returning the lever handle 302 to "running position". Failure to do so will leave the brakes as yet not subject to release as the vacuum in the vacuum chamber of the train stop D has been destroyed by the opening of the duplex control valve and the 15 pressure on both sides of the diaphragm 209 is balanced. This allows atmospheric pressure to enter the ports e into the chamber B and holds the valve 203 off of its seat, admitting air into the train pipe T, thus 20 destroying the vacuum therein.

By returning the handle 302 to "running position" a vacuum is again produced in the pipe 128, passages 132 and 131, pipe 130, passage d and chamber C, thus allowing atmospheric pressure on the upper side of the diaphragm 209 to force it downward into the chamber C, closing the valve 203 into its seat 202, as shown in Fig. 14.

- When the release cock handle 302 is placed 30 in "released position" and any remaining vacuum in the pipe 128 and passages 132 is destroyed, the suction on the valve v will be stopped and the magnets M and M' will be permitted to again attract the armature 45 to normal position for it is beyond the power 35 of the magnet to raise the armature 45 into normal position while there is any vacuum in the passages 132 under the valve v due to the atmospheric pressure on the top of the 40 valve v.

Operation.

The track is divided as usual into a series of blocks insulated from each other. A 45 single permanent track magnet associated with an electro-magnet control unit of opposite polarity are installed at the entrance of each block. The track magnet acting alone is capable of controlling the operation of the 50 train stopping means carried by the train every time a train passes over the magnet since it has a polarity opposite to that of one of the valve magnets. The electro-magnet control unit, however, is energized 55 whenever its circuit is closed by a train closing the track and line circuits of a system to provide clear signals and thus acts to divert the free field of the track magnet and thereby prevents the track magnet from 60 causing the train stopping mechanism of the train to operate. The installation of the electromagnet control unit is such that it will be energized on the approach of a train when the block ahead is clear or unoccupied, 65 and its circuit will not be closed by the ap-

proach of a train when the block ahead is occupied, thereby permitting the permanent track magnet to act upon the train stopping mechanism as will be later described. The reason the electromagnet control unit acts 70 upon the track magnet to divert its field is due to the fact that the former is stronger than the permanent track magnet and its polarity is opposite thereto. The electromagnet control unit may be operated in 75 several ways, one by use of a relay, the circuit of which is controlled by the block ahead, or it may be operated by reason of the fact that it is in circuit with the rails of the block. In the latter instance, how- 80 ever, the battery would have to be very strong and therefore to prevent excessive use of the battery it is preferably in circuit with a short track section of several rail lengths and this circuit is closed upon the 85 entrance of the first wheels therein, the wheels and axle acting as a switch in the circuit.

When a train passes over the track magnet its free field acts upon the inductor planes 90 of the duplex control valve F which causes a reversal of polarity in one of the armatures thereof and thus permits the release of the armature from the poles, installed as heretofore described in the duplex control valve, 95 and thereby permits the opening of the valve therein because of the air pressure normally exerted thereon, which action results in the stopping of the train.

The various pieces of mechanism which 100 have been heretofore described having been installed on a railway train in the manner and in the relative positions described, and as the connection flange 212 is inserted in the train vacuum pipe T in any convenient 105 position on the locomotive or vehicle, it will be seen that the chamber A of the train stop will be connected with the said train vacuum pipe and that the brake vacuum chamber is connected to the release cock 368 by the pipe 110 118 and the said release cock is connected to the duplex control valve by the pipe 128, the duplex control valve being also connected to the train stop D by the pipe 130, all as shown diagrammatically in Fig. 6. 115

It is to be understood that in the operation of this system a vacuum is normally maintained in the "brake vacuum chamber" which chamber is a part of the brake equipment, and it is not shown in the drawings 120 as such an apparatus is clearly understood.

In producing and maintaining the vacuum in the "brake vacuum chamber" air is also drawn from the chamber C of the stop valve D through the passage d, the pipe 130 and 125 passages 131. The air is also drawn from the passages 136, safety nipples 125 and passages 137. As the passages 131 are connected to the valve v air is also drawn through the passages 132 through the restricted passage- 130

way 128' (choke fitting), thence through the pipe 128, through the release cock 368 which is in normal position, and through the pipe 118 which connects into the brake vacuum chamber.

Because of the pressure vacuum which is maintained in the "brake vacuum chamber" a pressure vacuum will also be maintained in the pipes, passages, ports and chambers just specified. This being the case, the fluid pressure in the chamber C is reduced and the normal atmospheric pressure on the top of the diaphragm in the chamber B will force the diaphragm 209 down into the chamber C, closing the valve 203 onto its seat 202 as the effective area of the diaphragm is greater than the exposed area of the valve 203 in the chamber B.

The valve 203 will not be raised from its seat because the pressure in the chamber B, which enters through the radial ports e, is not sufficiently great to do so notwithstanding that there is a pressure "vacuum" in the vacuum train pipe and chamber A, because of the greater exposed area of the diaphragm 209 compared with the area of the valve 203.

As has been described, the duplex magnets M and M' are so arranged that one pair will have a polarity opposite to that of the other pair. That is, the south pole of one and the north pole of the other are in a line parallel to the center line of the railway track. The two valve units are provided to ensure that the polarity of one will always be opposite to that of the track magnet regardless of the direction that the locomotive or railway vehicle is running, and also regardless of the polarity of the track magnet. The valve equipped with the magnets having polarity opposite to the track magnet is the one that operates, so that only one valve operates at any particular time.

Assuming that the duplex control valve carried on the locomotive is out of the free field of the track magnet, the armature 45 will be held up against the pole piece dowels 42 by the magnetic attraction of the magnets M and M'. When the armature is in this position there will be a "vacuum" in the passages 131 and 132 as the atmospheric pressure on the under side of the valve v will have been depleted. The pressure, however, which acts upon the upper face of the valve v is insufficient to overcome magnetic attraction of the pole pieces for the armature.

When the locomotive or railway vehicle carrying the duplex control valve set passes over a track permanent magnet and the extending inductor planes P of these valves enter the free magnetic field of the track magnet, the polarity of the armature of the operative valve is reversed (the track permanent magnet being of much greater

magnetic strength than the valve magnets) due to magnetic induction. This condition of reversal is brought about when the inductor planes enter the free field of the track magnet and this condition exists so long as the inductor planes remain in the free field.

This reversal of polarity causes the armature 45 to be released and repelled from the pole piece dowels 42. When this action occurs the pressure on the top of the valve v forces it downward against the gasket 55 which serves as a seat, preventing the atmospheric pressure from entering into the passages 132. The air in the chamber 133 is admitted through the port 134, into the tube 131', into the pipe 130, through the passageway d, thence into the chamber C, destroying the vacuum therein, which results in the application of the train brakes.

When the air pressure in the chamber 133 is admitted through the port 134 and into the passage 131, the pressure carries the ball check valve 150 into one of the seats 145 and the ball check valve will seat itself into that seat which is the greater distance from the valve which was operated to admit the fluid pressure. The seating of the ball check valve 150 into the seat 145 prevents atmospheric pressure from being admitted to passage 132, through the other valve of the duplex valve which is in normal position.

The restoration to normal position of the apparatus is explained above in the description under the heading "Release cock."

In the interest of clearness the selected installation, which is one of many, showing the means for energizing the electrocontrol magnet 14 is illustrated in Fig. 19.

Referring to this figure, it is to be noted that all track and line relays are normally energized and the local-relay s controlling the circuit of the electrocontrol magnet 14 is normally de-energized, the main lead of the circuit controlling this relay being open. It is also to be noted that the armatures controlling the contacts x³, y³ and z³ are themselves controlled by the respective magnets of the track relays x, y and z, and that in Fig. 19 illustrating this installation the various armatures are, in the interest of clearness, shown at an exaggerated distance from each other.

Assuming that a train is passing through the installation with the block ahead of the train unoccupied and all apparatus in normal condition; when this train enters track section x', track relay x is shunted and opens a contact point x³ in one branch of the circuit from the battery s, s, controlling local relay s. As the train enters track section y' track relay y is shunted and a circuit is completed by the closing of contact y³ to energize relay s, which circuit is as follows: from positive side of battery s, s, to wire 130

1010, contact point y^3 of relay y , wires 1030, 1050 to contact 2140' of relay 2140; from point of relay 2140, wires 1070 and 1130, coils of relay s and wire 1000 to the negative side of battery. Relay s is therefore energized closing contact s' and the circuit to the electrocontrol magnet 14 is completed through its front contact point s' and its battery 1414 which results in neutralizing the effect of the permanent track magnet 13 by diverting the field, thus permitting the train to proceed without interference. When the block ahead is clear the above is the normal operation from either direction, (the train entering z' , track relay z being then operative instead of z as given above) and this is typical of all indication points for traffic in both directions.

Assuming now that the track section or block z' is occupied and a train approaches from z' , line relay 2140 will be deenergized due to the short circuiting of battery zz , which opens contact z^3 . Line relay 2140 thus being open, both branches of the circuit controlling relay s are broken and this relay cannot therefore be energized for supplying current to the electrocontrol magnet 14, for the purpose of neutralizing the effect of the track permanent magnet 13 by diverting its field, therefore in such case the permanent track magnet will be effective to cause an automatic stop operation of the locomotive apparatus and a consequent application of the brakes. The line relay control wires can be connected to points of a track relay at any distant point, as may be necessary.

As changes of construction could be made within the scope of my invention, it is intended that all matter contained in the above description or shown in the accompanying drawings shall be interpreted as illustrative and not in a limiting sense.

Having now described my invention, what I claim as new and desire to secure by Letters Patent is:

1. In an automatic train stop device for use with a vacuum air brake system, a plurality of valves controlling the vacuum in the ducts of said system, magnetic means for controlling each of said valves, one of said magnetic means having its respective poles arranged opposite to the poles of the other.

2. In an automatic train stop device for use with a vacuum air brake system, a plurality of valves controlling the vacuum in the ducts of said system, magnetic means for controlling each of said valves to maintain or destroy said vacuum, the magnets being so situated with respect to each other that the polarity of one magnet is opposite to the polarity of the other.

3. In an automatic train stop device for use with an automatic vacuum air brake system, a plurality of valves controlling the vacuum in the ducts of said system, mag-

netic means for controlling each of said valves to maintain or destroy the vacuum, the said magnetic means being so arranged that the north pole of each magnet is adjacent to and in line with the south pole of the other.

4. In a vacuum train stop device for use with a vacuum air brake system, duplex valves controlling the vacuum in the ducts of said system, magnetic means for controlling each of said valves to maintain or destroy said vacuum, the said magnetic means being so arranged that the north pole of each magnet is adjacent to and in line with the south pole of the other. 80

5. In a vacuum train stop device for use with a vacuum air brake system, a plurality of valves for controlling the vacuum in the ducts of said system, magnetic means for controlling each of said valves to maintain 85 or destroy the said vacuum, the magnets being so positioned with respect to each other that the polarity of one is opposite to the polarity of the other and the field of one magnet affects the field of the other thereby 90 causing the magnet of lesser strength to be in condition for operation.

6. In combination, an automatic train stop device for use with a vacuum air brake system, a plurality of valves controlling the 95 vacuum in the ducts of said system, magnetic means controlling each of said valves for maintaining or destroying the said vacuum, the magnets being so positioned with respect to each other that the polarity of one 100 magnet is opposite to the polarity of the other, said magnetic means normally maintaining the valves closed to maintain the vacuum in the ducts, and a polarized track magnet of greater power than said magnetic 105 means and through the magnetic field of which each of said magnetic means is movable to release the valve and destroy the vacuum.

7. In combination, an automatic train stop 110 device for use with a vacuum air brake system, a plurality of valves controlling the vacuum in the ducts of said system, magnetic means controlling each of said valves to maintain or to destroy the said vacuum, the magnets being so positioned with respect to each other that the polarity of one magnet 115 is opposite the polarity of the other, said magnetic means normally maintaining the valves closed to maintain the vacuum, and a polarized track magnet of greater power than said magnetic means, and through the magnetic field of which each of said magnetic means is movable, the track magnet effecting the release of one of the valves to 120 destroy the vacuum regardless of the position longitudinally of the permanent track magnet with respect to the line of track. 125

8. In combination, an automatic train stop device for use in a vacuum air brake sys- 130

- tem, a valve controlling the vacuum in the ducts of said system, magnetic means controlling the operation of said valve to maintain or destroy said vacuum, an inductor plane controlling the magnet of said valve, the said inductor plane being hollow but normally closed to the atmosphere, an air duct connecting the central hollow portion of the inductor plane with the duct or chamber controlled by said valve, means for connecting the vacuum train pipe with the said air duct, and means for effecting the destruction of the vacuum in the vacuum train pipe by a rupture of the inductor plane.
9. In combination, an automatic train stop device for use with a vacuum air brake system, a valve controlling the vacuum in the ducts of said system, magnetic means controlling the operation of said valve to maintain or destroy said vacuum, the said magnetic means normally maintaining the vacuum in the ducts, an inductor plane connected to said valve, the said inductor plane having a hollow core connected to the duct controlled by the valve leading to the vacuum brake pipe so that upon a rupture of the inductor plane the vacuum will be destroyed to effect the application of the brakes.
10. In an automatic train stop device for use with a vacuum brake system, a duplex valve unit including a plurality of valves, ducts controlled by said valves, magnetic means for controlling each of said valves, the said magnetic means being so arranged that the north pole of each magnet is adjacent to and in line with the south pole of the other, and so arranged as to pass through the operative field of a permanent track magnet, only one of said valves being adapted to be operated at a given time by said magnetic means and a check valve for preventing the passage of pressure past one of said valves when the other valve is operated.
11. In an automatic train stop device for use with a vacuum brake system, a duplex valve unit including a plurality of valves, ducts controlled by said valves, an automatic train stop having a pressure actuated valve normally preventing the entrance of air to the train vacuum pipe, means connecting one of said ducts with the vacuum chamber of the brake equipment, means for connecting the other of said ducts with said train stop, a chamber in said valve unit open to atmosphere, magnetic means for normally holding each of said valves in closed position to prevent communication between said ducts and said chamber, said valves being so constructed that when they are released by said magnetic means the duct leading to the vacuum chamber of the brake equipment will be closed and the duct leading to said train stop will communicate with said chamber which is open to atmosphere.
12. In an apparatus of the class described, a control valve unit structure comprising a casing, magnet cores secured to said casing, pole pieces secured thereto, a permanent magnet and pole piece dowels secured to said pole pieces, a valve bushing in juxtaposition to said pole piece dowels, an armature guided by said bushing and coacting with said pole piece dowels, a valve seat in said bushing and a valve coacting therewith carried by said armature.
13. In an apparatus of the class described, a control valve unit structure comprising a casing, magnet cores secured to said casing, pole pieces secured thereto, a permanent magnet and pole piece dowels secured to said pole pieces, a valve bushing in juxtaposition to said pole piece dowels, an armature guided by said bushing and coacting with said pole piece dowels, a valve seat in said bushing, two ducts formed in said control valve unit, a port formed in said bushing beyond said valve seat and communicating with one of said ducts, and a valve carried by said armature comprising two portions, one a disc portion adapted to be held against said seat by said magnet to control the passage of pressure through said port to one of said ducts, and the other an annular portion adapted to control the communication from one duct to the other.
14. In an apparatus of the class described for use in a vacuum brake system, a train stop having two outer chambers and an intermediate chamber, a diaphragm between one outer chamber and the intermediate chamber, a valve seat between the other outer chamber and the intermediate chamber, a valve carried by said diaphragm coacting therewith, means for applying a vacuum to said outer chambers and ports in said intermediate chamber leading to atmosphere, the atmospheric pressure in the intermediate chamber serving to normally hold said valve on its seat.
15. In an apparatus of the class described for use in a vacuum brake system, a train stop having two outer chambers and an intermediate chamber, a diaphragm between one outer chamber and the intermediate chamber, a valve seat between the other outer chamber and the intermediate chamber, a valve carried by said diaphragm coacting therewith, means for applying a vacuum to said outer chambers and ports in said intermediate chamber leading to atmosphere, the atmospheric pressure in the intermediate chamber serving to normally hold said valve on its seat, a magnetic valve, a duct whose communication with atmosphere is controlled by said valve, said duct communicating with the chamber adjacent said diaphragm, and said magnetic valve being adapted to admit atmospheric pressure to said last named chamber to permit the valve carried by said diaphragm to be lifted to

break the vacuum in the other outer chamber.

16. In an apparatus of the class described for use with a vacuum brake system, a train stop having an upper, a lower and an intermediate chamber, means for connecting the upper chamber with a train vacuum pipe, ports in the intermediate chamber leading to atmosphere, a valve normally preventing communication between the upper and intermediate chambers, a diaphragm between the intermediate and lower chambers to which said valve is secured, means for normally maintaining a vacuum in the lower chamber to keep said valve closed and means for breaking said vacuum to unbalance the pressures on said diaphragm and cause said valve to open communication between the train vacuum-pipe and atmosphere.
17. In an apparatus of the class described for use with a vacuum brake system, a train stop comprising a valve body having an upper and an intermediate chamber formed therein, a valve seat between said chambers, a valve guided in the upper chamber and coacting with said valve seat, ports in the intermediate chamber opening to atmosphere, a flexible diaphragm of greater area

than said valve secured below the intermediate chamber, a cap having a lower chamber formed therein detachably secured to said valve body, a main connection flange secured to the upper portion of said valve body, said main connection flange having a passage therein connecting the said upper chamber with the train vacuum pipe, and a duct connected with the said lower chamber.

18. In an automatic train stop device for use with a vacuum air brake system, a permanent magnet, and a valve operated directly by said magnet to govern the vacuum in the ducts of said system whereby the vacuum is either maintained or destroyed.

19. In an automatic train stop device for use with a vacuum air brake system, a permanent magnet, and a valve operated directly by said magnet to govern the vacuum in the ducts of said system whereby the vacuum is either maintained or destroyed as the magnetic flux in said magnet is varied, said magnet being positioned to be subjected to external magnetic influences.

In witness whereof I have hereunto set my hand this 15th day of January, 1921.

HOWARD S. FOLKER.
